(57) **CLAIM**

The ornamental design for a bracket for a reflector of a light fixture, as shown and described.

DESCRIPTION

FIG. 1 is a left front perspective view depicting a bracket for a reflector of a light fixture;

FIG. 2 is a right rear perspective view depicting the bracket of FIG. 1;

FIG. 3 is a left side elevational view depicting the bracket of FIG. 1, the right side view being a mirror image thereof;

FIG. 4 is a front elevational view depicting the bracket of FIG. 1;

FIG. 5 is a rear elevational view depicting the bracket of FIG. 1;

FIG. 6 is a top plan view depicting the bracket of FIG. 1; and,

FIG. 7 is a bottom plan view depicting the bracket of FIG. 1.

The details shown in broken lines in the figures form no part of the claimed design of the bracket. Any details shown in dot-dash broken lines in the figures define the bounds of a portion of the claimed design and form no part of the claimed design. The surface shading shown in the figures represent contour and not surface ornamentation.
